UNITED STATES PATENT OFFICE

148,239

DESIGN FOR A PIPE BOWL

Philip S. Harper, Chicago, Ill., assignor to Harper-Wyman Company, Chicago, Ill., a corporation of Illinois

Application December 14, 1946, Serial No. 135,524

Term of patent 14 years

(Cl. D85—8)

To all whom it may concern:

Be it known that I, Philip S. Harper, a citizen of the United States, residing at Chicago, in the county of Cook and State of Illinois, have invented a new, original, and ornamental Design for a Pipe Bowl, of which the following is a specification, reference being had to the accompanying drawing, forming part thereof.

This application is a continuation-in-part of application Serial No. D. 129,321, filed May 4, 1946.

Fig. 1 is a perspective view of a pipe bowl embodying my new design; and

Fig. 2 is a side elevational view of the pipe bowl.

I claim:

The ornamental design for a pipe bowl, as shown and described.

PHILIP S. HARPER.
